UNITED STATES PATENT OFFICE

JOHN H. WELLER AND ROY S. NEWTON, OF NEW HAVEN, CONNECTICUT, ASSIGNEES TO SARGENT & COMPANY, OF NEW HAVEN, CONNECTICUT

PLANE

Application filed January 7, 1930. Serial No. 419,054.

Our invention relates to a plane and more particularly to a plane having an adjustable bit for varying the thickness of the chips cut by the plane.

5 In the usual plane the plane of the bit bears a fixed angular relationship to the bottom of the plane which limits the utility of the plane and the quality of work which may be accomplished therewith.

10 The general object of the present invention is to provide a plane in which the angle of the bit may be varied according to the depth of the cut or character of the grain of the wood acted on.

15 In a more specific aspect it is an object of the invention to provide a plane having a bit supporting frog which is adjustable with respect to the bed of the plane whereby the plane of the bit may be readily varied with 20 respect to the bottom of the plane.

A further object of the invention is to provide a plane in which chips are prevented from passing into the plane through the throat except in front of the bit.

25 To these and other ends, the invention consists of the novel features and combination of parts to be hereinafter described and claimed.

In the drawings,

30 Fig. 1 is an elevational view in section of a plane according to our invention;

Fig. 2 is a sectional view along line 2—2 of Fig. 1;

35 Fig. 3 is a sectional view along line 3—3 of Fig. 1;

Fig. 4 is a sectional view along line 4—4 of Fig. 1;

Fig. 5 is a view similar to Fig. 1, but showing another form of the invention embodying additional improvements; and

40 Fig. 6 is a sectional view along line 6—6 of Fig. 5.

Referring to the drawings in which we have shown a preferred embodiment of our 45 invention, the reference numeral 10 indicates in general the stock or bed of the plane, which is preferably made out of metal and is of the usual cross sectional shape. The front handle, of usual type, is indicated at 50 11, while the reference numeral 12 indicates

the rear handle also of usual type. The bit or plane iron 13 is clamped against a frog 14 by means of clamp 15 which is provided with the usual clamping finger 16, the usual screw 17 passing through the clamp and into the frog 14 to secure the clamp to the frog. At the lower rear part of the frog 14, the latter carries a projecting lug 18 in which the lower end portion of adjusting screw 19 is freely rotatable. The opposite or upper end of adjusting screw 19 has a bearing in a lug 20, projecting from the rear upper portion of the frog 14 and similar to lug 18. Axial movement of screw 19 in one direction is prevented by milled head 21, and in the opposite direction by collar 22 and pin 23, collar 22 bearing against the lower face of lug 18, while milled head 21 rests on adjusting lever 24, which is provided near one end thereof with a pin 25 received in an opening in lug 20.

Lever 24 is provided with a nose 26 received in a longitudinal slot 27 in plane iron 13 and provides for the transverse adjustment of plane iron 13 by movement of lever 24 about the axis of pin 25. Received on screw 19 between lugs 18 and 20 and providing for the longitudinal adjustment of plane iron 13 is a nut 28 having its inner end received in a slot 29 in frog 14 and having a finger 30 which may be received in one of a plurality of openings 31 in plane iron 13.

In the usual plane the frog is formed integrally with respect to the stock or bed or secured thereto immovably. Herein the frog 14 is formed separately from the bed of the plane and is pivotally mounted thereon, as by means of pin 32, which extends transversely through the bed of the plane and through the lower end of the frog. The bed of the plane is provided with a thickened portion 33 which is channeled at 34 for the reception of wedge 35, which is supported for movement towards and away 35 from frog 14 on bearing surfaces 36, 37, 38 and 39, wedge 35 being provided with a substantially semi-cylindrical upper surface 40, which engages the under side of frog 14, as at 41 and 42, and by movement of wedge 100

along bearing surfaces 36, 37, 38 and 39 swings frog 14 about pin 32. Wedge 35 may be readily moved along bearing surfaces 36, 37, 38 and 39 by means of milled nut 43, which is provided with a groove or reduced portion 44 in which spaced lugs 45 and 46 on plane bottom 10 are received, nut 43 being threaded for the reception of threaded stem 47 having at one end thereof a reduced portion 48 fixed in wedge 35, the end of stem 47 being headed over at 49 to prevent axial movement of stem 47 with respect to wedge 35.

Frog 14 is provided with a recess 50, at the lower end of which is a chamfered opening 51 for the reception of screw 52, the lower end of which is received in threaded opening 53 in plane bottom 10. When frog 14 has been adjusted to any desired position by movement of wedge 35, screw 52 serves to force frog 14 against wedge 35, screw 52 and wedge 35 cooperating to hold the frog immovably in place.

The plane shown in Figures 5 and 6 of the drawings is provided with a bed 54 on which frog 55 is mounted for pivotal movement by means of pin 56 passing transversely through bed 54 and through the lower end of frog 55, frog 55 serving to support bit 57. Longitudinal movement of bit 57 is effected in the more or less usual manner by means of lever 58 pivotally supported on pin 59 in frog 55, lever 58 being provided at one end with a nose 60, and at the other end with a yoke, which is received in a groove 61 in nut 62, the latter having a threaded axial opening 63 in which threaded stem 64 is received, stem 64 being fixed in the usual manner in frog 55 and extending rearwardly therefrom. Transverse movement of bit 57 is effected in the usual manner by means of lever 65, pivotally supported on the upper end of frog 55, at 66, and having a nose 67 which is received in the usual longitudinal slot 68 in bit 57. The usual clamp 69 is secured to frog 55 by means of screw 70 which extends through enlarged opening 71 in frog 55 and is received in a threaded opening 72 in lug 73 of bed 54.

50. Mounted on the threaded end of screw 70 between lug 73 and frog 55 are milled nuts 74 and 75, of which nut 74 engages the under side of frog 55 and cooperates with the head 76 of screw 70 to secure the clamp 55. 69 and bit 57 against frog 55. Nut 75 engages a washer 77 and forces the latter against lug 73 to lock the screw 70 against movement. The position of frog 55, and thereby the angle of bit 57 with respect to the bottom of the plane, may be readily varied by adjusting the position of screw 70 in opening 72, nut 75 serving to lock the screw in any position of adjustment.

The cutting edge 78 of bit 57 extends 65 through opening 79 in bed 54, the position

of the lower end of bit 57 in opening 79 varying according to the adjustment of frog 55. In order to prevent chips or the like from passing through opening 79 behind bit 57, a plate 80 is provided which is carried on the inner surface of the bottom of the plane, plate 80 having a tapered edge 81 adjacent bit 57, tapered edge 81 being bent slightly downwardly and substantially filling the opening behind bit 57. Plate 80 is automatically adjusted in position as frog 55 is adjusted by means of link 82, one end of which is mounted in slot 83 in frog 55 on pin 84, while the opposite end is mounted on pin 85 in bell crank lever 86. Lever 86 is mounted on pin 87 in bed 54, and is provided with a finger 88 received in a suitable opening in plate 80. As frog 55 is adjusted by means of screw 70 and nut 74, link 82 swings lever 86 to maintain the edge 81 of plate 80 in proper position behind bit 57.

It will be readily understood from the above description of the invention that we have provided a plane in which not only may the plane of the bit be adjusted with respect to the work engaging faces of the plane, but also a plane in which provision is made for preventing chips from passing into the plane except through the throat normally intended to receive the chips.

While we have shown preferred embodiments of our invention, it will be understood that it is not to be limited to all the details shown but is capable of modification and variation within the spirit of the invention and the scope of the appended claims.

What we claim is:

1. In a plane, a bed provided with a work engaging face and an opening extending through the face, a bit extending through said opening, means for adjusting the plane of the bit with respect to the work engaging face, means movable into position behind said bit for preventing chips from passing through the opening behind the bit, and means associated with both of said means for controlling the movement of the second-named means as the first-named means is adjusted.

2. In a plane, a bed provided with a work engaging face and an opening extending therethrough, a bit extending through said opening, means for adjusting the plane of the bit with respect to the work engaging face, means for preventing the passage of chips through the opening behind the bit, and means connected to said adjusting means for adjusting the position of said last-named means as the angle of the bit is adjusted.

3. In a plane, a bed provided with a work engaging face and having an opening extending therethrough, a bit extending

through said opening, means for adjusting the plane of the bit with respect to the work engaging face, and means movable into position behind the bit to prevent the passage of chips through the opening behind the bit, the movement of said last-named means being controlled by the adjustment of the bit.

4. In a plane, a bed provided with a work 10 engaging face and an opening extending therethrough, a bit extending through said opening, an adjustable frog for supporting said bit at a plurality of angles with respect to the work engaging face, means movable 15 into position behind the bit to prevent the passage of chips through the opening behind the bit, and a connection between said last-named means and the frog whereby adjustment of the frog controls the movement of 20 said last-named means.

5. In a plane, a bed provided with a work 25 engaging face, a bit, a frog on which said bit is supported, and means for adjusting said frog to vary the angle of the plane of the bit with respect to the work engaging 30 face, said last-named means including an adjustable screw passing through the frog and into the bed, said screw serving to secure the bit to the frog.

6. In a plane, a bed provided with a work 35 engaging face, a bit, a frog on which said bit is supported, and means for adjusting said frog to vary the angle of the plane of the bit with respect to the work engaging 40 face, said last-named means including an adjustable screw passing through the frog and into the bed and a nut received on said screw and adapted to bear against the bed to hold the screw against movement.

7. In a plane, a bed provided with a work 45 engaging face, a bit, a frog on which said bit is supported, and means for adjusting said frog to vary the angle of the plane of the bit with respect to the work engaging 50 face, said last-named means including an adjustable screw passing through the frog and into the bed and a pair of nuts mounted on said screw, one of said nuts being adapted to bear against the bed to hold the screw against movement and the other of said nuts bearing against the frog to position the latter.

8. In a plane, a bed provided with a work 55 engaging face, a bit, a frog on which said bit is supported, said frog being adjustably mounted on said base to vary the angle of the plane of the bit with respect to the work engaging face, and common means for holding said bit against movement on said frog and said frog against movement on said base.

9. In a plane, a bed provided with a work 60 engaging face, a bit, a frog on which said bit is supported, pivotal means for mounting said frog on said bed to vary the angle

of the plane of the bit with respect to the work engaging face, and common means for holding said bit against movement on said frog and said frog against movement on said base.

In witness whereof, we have hereunto set our hands this 26 day of December, 1929.

JOHN H. WELLER.
ROY S. NEWTON.
